UNITED STATES PATENT OFFICE.

CHARLES MORGAN, OF FREEPORT, ILLINOIS, ASSIGNOR TO ARCADE MANUFACTURING COMPANY, OF FREEPORT, ILLINOIS, A CORPORATION OF ILLINOIS.

CORK-PULLER.

SPECIFICATION forming part of Letters Patent No. 690,070, dated December 31, 1901.

Application filed April 30, 1900. Serial No. 14,826. (No model.)

To all whom it may concern:

Be it known that I, CHARLES MORGAN, a citizen of the United States of America, residing at Freeport, in the county of Stephenson and State of Illinois, have invented certain new and useful Improvements in Cork-Pullers, of which the following is a specification.

My invention relates to certain improvements by means of which I enable the cork-drawing apparatus in a cork-puller to be adjusted so as to vary the limit to which the cork is withdrawn, so that in cases where it is desirable to start the cork without removing it entirely from the bottle it can be withdrawn a short distance and left in the latter.

The invention consists in certain novel characteristics which will appear from the following description and claims.

The drawings illustrate the preferred construction by means of fifteen figures, showing the cork-puller in various positions and certain of the parts thereof in detail views.

Figure 1 is a side elevation of a complete puller in its normal position ready for use.

Fig. 2 is a horizontal section looking downward in line 2 2 of Fig. 1. Fig. 3 is a vertical section of the case, showing the working parts of the puller in side elevation and in different positions from Fig. 1. Fig. 4 is a view similar to Fig. 3 with the parts in a third position. Fig. 5 is a section in line 5 5 of Fig. 2 looking in the direction of the arrow 5 of said figure and showing the parts in a fourth position. Fig. 6 is a vertical section in line 6 6 of Fig. 1 looking in the direction of the arrow 6 of said figure. Fig. 7 is a similar section in line 7 7 of said figure. Fig. 8 is a vertical detail section in line 8 8 of Fig. 1 looking downward. Fig. 9 is a similar section in line 9 9 of Fig. 3. Fig. 10 is a similar section in line 10 10 of Fig. 3. Fig. 11 is a perspective view of the corkscrew-carrier. Fig. 12 is a perspective of the nut-operating lever. Fig. 13 is a second perspective of the same, showing the opposite side. Fig. 14 is a perspective of a pivoted guide-bar, and Fig. 15 is a perspective of a dog which operates the bottle-holder to control the longitudinal movement of the bottle-holder.

The various parts of the cork-puller will be

described specifically and for the purpose of clearly setting forth their exact construction. It is not, however, the intention to limit the claims thereby, as certain features of the invention are wholly independent of any particular form or arrangement of the operating parts.

Referring to the drawings, A is a suitable frame or casing made up of two side plates a a' , (see Fig. 6,) secured together by means of two screws a^2 a^3 , the latter of which furnishes a pivot upon which a link b is pivoted at one end, the other end being pivoted at b' to a handle B between the ends of the latter. The free end of the handle is provided with a grip b^2 and the other end is pivoted at b^3 to a corkscrew-carrier C, in which is journaled a corkscrew D. The carrier is reciprocated longitudinally of the case by the handle and works in a cylindrical guideway a^4 , said guideway being slotted upon the side next to the handle at a^5 to allow said handle to work up and down in the case and upon the opposite side at a^6 to accommodate an extension e of the carrier and also an extension e of a nut E, also working in the cylindrical guideway. The nut is bored to fit the corkscrew, and alternately enforces and prevents rotation of the latter, depending upon whether it is held stationary or moved in unison with the corkscrew-carrier. The nut is limited as to its upward movement by the engagement of a pin e' with a lug a^f , and in its downward movement by the engagement of the extension e with a knuckle f upon a plate F. Said plate F is extended upwardly in the shape of two arms f', guided longitudinally in vertically-arranged guides a^7 a^8 in the casing and limited in their travel by means of pins f² working in slots a^9 a^9 in the guides. Said plate carries pivoted clamping-jaws f³ f⁴, containing elastic grips f⁵ f⁶ and provided with handles f⁷ f⁸, by means of which they may be tightened upon the neck of a bottle.

The cork-puller belongs to the class in which the downward movement of the corkscrew forces the latter into the cork and the upward movement withdraws the cork to a predetermined extent and then withdraws the corkscrew from the cork, and it is intended to

provide means for varying the extent to which the cork is withdrawn from the bottle by varying the position of the latter with respect to the casing. This is accomplished in 5 the construction here shown by means of a dog G, capable of alternate engagement with a lug a^e on the casing and with the extension e of the nut. The upper end of the dog has a hook g to engage said extension. The dog 10 is pivoted at g' to the knuckle f and has a lateral extension g² passing outside of the case and up alongside of the same and terminating in a handle g³, by means of which the dog may be swung back and forth. When 15 the dog is in engagement with the lug a^e , it holds the bottle-grip down and causes the cork to be wholly withdrawn from the bottle. When the dog is engaged with the extension e, however, the bottle is raised, so that the corkscrew 20 is withdrawn from the cork before the latter leaves the bottle.

The rotation of the corkscrew both in entering and withdrawing from the cork is caused by the nut E, and the mechanism for 25 operating said nut by means of the corkscrew-carrier consists of a nut-operating lever H and a pivoted guiding-bar I, coöperating with certain guides and stops upon the casing and the extension e upon the corkscrew-carrier. 30 Looking at Fig. 11 said extension bears a shoulder c', a notch c², and two tapered lugs c³ c⁴ pointed toward each other. The guide-bar I is pivoted at i to the casing and bears a guiding-rib i² and inclined laterally-extending shoulders i^c i^e i^m iⁿ. A spring J bears upon it to throw it to the left. The nut-operating lever H is pivoted at h to the extension e of the nut. It has two lugs h' h², which embrace the rib i^a of the bar. It has a lug h³, 40 which engages the corkscrew-carrier by means of the shoulder c', a hook h⁴, which engages the notch c² of the carrier, and a lug h⁵, which may engage a lug a^e of the casing to prevent the nut from dropping at certain parts of the 45 operation.

The operation of the cork-pulling mechanism is as follows: Fig. 1, as before stated, shows the cork-puller ready to commence operations. The neck of the bottle should be inserted in the clamp and tightly gripped by 50 means of the handles f⁷ f⁸. The handle b² is then raised, lowering the corkscrew-carrier. The lever H being hooked into the notch of the carrier, the nut E is carried downward 55 until it reaches the downward limit of its travel. (Shown in Fig. 3.) The lug c³ on the carrier then strikes the shoulder i^m, crowding the guide-bar and the guided lever to the right and unhooking the lever from the carrier. As 60 the upward movement of the handle continues the carrier passes downward, crowding the corkscrew through the nut, and thereby rotating it to assist its entrance into the cork. Just before the corkscrew-carrier reaches its 65 lowest point the lug c⁴ of the carrier rides up the shoulder i^c of the guide-bar and assists

the spring J to crowd the guide-bar into its original position, as is shown in Fig. 4, said guide-bar carrying the lever with it and hooking the lug h³ over the shoulder c' of the carrier. As the movement of the handle is reversed the carrier rises, taking the nut with it, thereby preventing rotation of the corkscrew and drawing the cork. When, however, the pointed lug c³ of the carrier reaches 75 the shoulder i^c of the guide-bar, it crowds the guide-bar to the right, as seen in Fig. 5, unhooking the lever from the carrier and throwing it over, so that in case the nut drops it will be supported by the lug a^e. The nut 80 having risen sufficiently to bring the pin e' against the lug a^e is checked in its upward movement, and as the carrier continues the corkscrew is rotated backward and withdrawn from the nut. The upward limit of 85 the travel of the nut being fixed with relation to the casing, the extent to which the cork is withdrawn depends upon the position of the bottle with relation to the casing, and two positions are provided for in the construction 90 here shown. Fig. 1 shows the parts arranged to hold the bottle-grip in the lower of these two positions, the dog G being thrown to the right and being shown in engagement with the lug a^e of the casing. This arrangement 95 of the parts preferably causes the cork to be entirely withdrawn. If for any reason it is desired to leave the cork in the bottle, the dog is thrown to the left by means of the handle g³, so that it engages the extension e of 100 the nut and is carried upward thereby, as illustrated in Fig. 5. This upward movement checks the withdrawal of the cork and subtracts just so much from the extent to which the latter is withdrawn. It should be noticed 105 that the dog is so pivoted as to be held by gravity in either of its two positions. If it is thrown into the position shown in Figs. 3 and 5 while the nut is above it, the extension of the nut merely crowds it toward the right 110 as it comes down, and the dog is returned by gravity as soon as the extension passes below the hook.

I claim as new and desire to secure by Letters Patent—

1. In a cork-puller, the combination with a frame, of a longitudinally-reciprocating nut guided therein, a reciprocating corkscrew rotated by the nut, a bottle-holding device supported by the frame, and movable longitudinally thereof, means for limiting the travel of the nut and means for moving the bottle-holding device to vary the distance between it and the nut when the latter is at the end of its travel away from said device; substantially 125 as described.

2. In a cork-puller, the combination with a frame, of a longitudinally-reciprocating corkscrew supported therein, a longitudinally-reciprocating corkscrew - rotating nut also 130 guided in the frame, a longitudinally-movable bottle-holding device, also guided in the frame

and means for alternately engaging said device with said nut and disengaging it therefrom; substantially as described.

3. In a cork-puller, the combination with a frame, a longitudinally-reciprocating corkscrew and means for rotating the same, of a longitudinally-movable device for grasping and holding the bottle provided with means for alternately engaging it with and disengaging it from the frame, thereby alternately preventing and permitting its longitudinal movement; substantially as described.

4. In a cork-puller, the combination with a frame, a longitudinally-reciprocating corkscrew and a longitudinally-reciprocating nut, of a longitudinally-movable bottle-holding device provided with means for alternately engaging it with the frame and with the nut, thereby alternately holding it stationary with respect to the frame and moving it in unison with the nut; substantially as described.

5. The combination with the frame, A, of the longitudinally-reciprocating corkscrew-

carrier, C, guided therein and having the shoulder, c' , the notch, c^2 , and the lugs, c^3 , c^4 , the corkscrew, D, journaled in the carrier, the nut, E, threaded to the corkscrew and guided in the frame, the guide-bar, I, pivoted to the frame and having the guiding-rib, i^a , and the inclined shoulders, i^c , i^e , i^m , i^n , adapted to engage the lugs, c^3 , c^4 , and the lever, H, pivoted to the nut and having the lugs, h' , h^3 , guided upon the rib, i^a , of the bar, the hook, h^3 , adapted to engage the shoulder, c' , of the carrier, and the hook, h^4 , adapted to engage the notch, c^2 , of said carrier; substantially as described.

In witness whereof I have hereunto set my hand, at Freeport, in the county of Stephenson and State of Illinois, this 24th day of April, A. D. 1900.

CHARLES MORGAN.
